 tion of New York

Application November 6, 1937, Serial No. 173,107

7 Claims. (Cl. 221—64)

The invention relates to containers and more particularly to that type commonly referred to as dispensing containers which generally include a movable closure whereby the dispensing openings of said containers may be opened and closed at will.

The invention has for its object to provide a container of the indicated class which is simple in construction and of maximum efficiency in operation. The invention contemplates further a novel construction which is specially adapted for use in connection with containers made of cardboard and other non-metallic materials. Other more specific objects will appear from the description hereinafter and the features of novelty will be pointed out in the claims.

In the accompanying drawing which illustrates examples of the invention without defining its limits, Fig. 1 is a sectional elevation of a container embodying the novel features; Fig. 2 is a similar view on the line 2—2 of Fig. 1; Fig. 3 is a plan view with parts broken away and in section; Fig. 4 is a face view of another form of closure for the container; Fig. 5 is a section thereof on the line 5—5 of Fig. 4; Fig. 6 is a face view of still another form of said closure; Fig. 7 is a sectional view on the line 7—7 of Fig. 6; Fig. 8 is a face view of a further form of the closure, Fig. 9 is a sectional view on the line 9—9 of Fig. 8, and Fig. 10 is a detail fragmentary section illustrating another form of the invention.

In the form shown in Figs. 1, 2 and 3, the novel container comprises a receptacle consisting of a main section or body 10 and a secondary section or sleeve 11 externally fitted upon said main section 10 and fastened in place thereon in any suitable manner, as by gluing. The main section or body 10 is preferably cylindrical in form with its upper end open and its lower end provided with a bottom in any conventional way; the secondary section or sleeve 11 is of corresponding cylindrical form and internally dimensioned to fit over the main section 10 in surface engagement therewith as shown in Figs. 1 and 2.

The container further includes a disk 12 dimensioned to snugly or frictionally fit the interior of the secondary section or sleeve 11, and resting upon and against the open end of the main section or body 10. The disk 12 is apertured in dependence upon the type of container with which it is to be combined and in accordance with the material for which said container is designed; in other words, the disk 12 may be apertured to sprinkle the contents of the container or to pour said contents therefrom. In the illustrated form of the container, the disk 12 is provided with a pouring aperture 13 to exemplify the aforesaid apertured arrangement. The aperture 13 or its equivalent is controlled by means of a rotat-

able closure 14 provided with a pouring opening 15 arranged to be adjusted into and out of registry with the pouring aperture 13 to selectively open and close the same at will; it will be understood that the closure 14 is always apertured in a manner corresponding to the aperture arrangement of the disk 12 and to enable the apertured portion of the latter and the apertured portion of the closure 14 to be brought into and out of registry with each other by rotatably adjusting said closure 14. The closure 14, which is in the form of a disk dimensioned to easily and rotatably fit within the secondary section or sleeve 11, lies in surface engagement with and rests upon the apertured disk 12 and is maintained in its assembled relation in any convenient and suitable manner; in the preferred construction the disk 12 projects beneath an internal annular bead 16 formed preferably at the outer end of the secondary section or sleeve 11. In practice the bead 16 or its equivalent is in such relation to the disk 12 as not to develop any material restraining force thereon or to otherwise interfere with the rotation of the closure 14 but at the same time to maintain said closure 14 in place as shown in Figs. 1 and 2. Any suitable operating means may be provided to facilitate the rotation of the closure 14 at will, said operating means being shown in Figs. 1, 2 and 3, in the form of a hollow rib or projection 17 extending diametrically across said closure 14 and preferably comprising an integral part thereof; as illustrated in Figs. 1 and 2 the rib 17 projects upwardly beyond the outer face of the closure 14 and constitutes a finger-piece for rotatably adjusting the same.

Any convenient method may be followed in the construction and assembling of the parts of the container shown in Figs. 1, 2 and 3. It being assumed that the main section or body 10 and the secondary section or sleeve 11 have been previously produced in the desired co-operating dimensions, the outer end of the sleeve 11 may be spun or otherwise manipulated to produce the internal annular bead 16 after which the closure 14 is placed within said sleeve 11 from its lower end so as to rest against said bead 16. The apertured disk 12 is then correspondingly introduced into said sleeve 11 and shifted lengthwise thereof until it engages the closure 14; the disk 12 is adjusted in the manner set forth to force the closure 14 into contact with the bead 16 without however clamping said closure 14 immovably against the latter, or in other words, without sufficient pressure to interfere with its ability to rotate in the intended manner. Because of the fact that the disk 12 fits snugly within the sleeve 11, it will be securely held in place therein by friction and accordingly will maintain the closure 14 in position in said sleeve. The sleeve 11 with 60

the disk 12 and closure 14 assembled therein, may then be placed over the open end of the body 10 in telescopic engagement therewith and adjusted lengthwise of said body 10 until the disk 12 rests 5 against and upon said open end of said body 10, as shown in Figs. 1 and 2. The sleeves 11 may be fastened in place on the body 10 by gluing or cementing or in any other convenient manner, suitable to the material of which the parts are 10 made.

With the aforesaid method, the main section 10 and the secondary section 11 of the container may be separately constructed as independent units and then combined in a simple manner to 15 provide the complete and finished container. It will, of course, be obvious that the construction and assembling of the parts of the container may be carried out in various other ways and sequences without in any way changing the final 20 product.

With the method of construction and assembling previously described herein, the assembled sleeve 11, disk 12, and closure 14, constitute a cover unit which may be combined with and fixed 25 upon the main section or body 10 after the latter has received the material it is intended to contain. The cover unit, as such, may be readily combined with any co-operating main section or body 10 as will be obvious.

30 In any case, when it is desired to remove any part of the contents of the container, it is simply necessary to rotatably adjust the closure 14 until the opening 15 or its equivalent registers with the aperture 13 or its equivalent of the disk 12. Communication with the interior of the container is 35 thereby established and it is merely necessary to invert or otherwise manipulate the latter to remove as much of said contents as may be desired at the time. To cut off communication with the 40 interior of the container or in other words, to close the same, it is necessary only to rotatably adjust the closure 14 to an extent sufficient to move its opening 15 out of registry with the aperture 13 of the disk 12. With the opening 15 and the aperture 13 out of registry with each other, 45 the closure 14 acts as a seal to effectively close the container and prevent unintentional spilling of its contents.

With the novel construction described hereinbefore and illustrated in Figs. 1 and 2 of the drawing, the main section or body 10 and the secondary section or sleeve 11 may be made of cardboard, metal or any other suitable material, or one of said sections may be made of metal and the other of cardboard or the like, or said sections 50 may be constructed of other combinations of materials adapted for the purpose. The disk 12 may be made of cardboard or its equivalent, or of metal, whichever is preferred, and the closure 14 likewise may be made of any suitable material 55 although in its preferred form said closure 14 is constructed of metal.

In the form shown in Figs. 4 and 5, the closure 14^a is provided with hollow ribs or projections 17^a located in spaced relation to each other diametrically of said closure 14^a as illustrated. The closure 14^a may include a pouring opening 15^a with any other type of opening or openings dependent upon the type of container for which it 60 is designed.

70 The hollow rib or projection 17 of the closure 14 and the hollow ribs or projections 17^a of the closure 14^a may be produced by being stamped from the material or the latter may be molded 75 or otherwise manipulated to provide said ribs.

The closure 14^b illustrated in Figs. 6 and 7, includes a peripheral projection 17^b preferably formed by cutting the material inwardly at the periphery of said closure 14^b and shaping the tongue produced by such cutting, for instance, as shown in Fig. 7. The closure 14^b also may include a pouring opening 15^b or any other type of opening or openings suitable to the purpose for which said closure 14^b is intended.

It will be understood that the ribs 17 and 17^a 10 instead of being in the cross-sectional form illustrated in Figs. 2 and 5 respectively, may be made and shaped in a manner corresponding to the cross-sectional shape of the projection 17^b of Fig. 7, if this should be preferred or desired. 15

As illustrated in Figs. 8 and 9, the means whereby the closure 14^c shown therein is rotated consists of a head or finger-piece 17^c secured preferably at the centre of said closure 14^c in any convenient manner as by means of a rivet 17^d. 20 The closure 14^c in its illustrated form also includes a pouring opening 15^c, it being understood that the latter may be replaced by any other suitable type of opening or openings as in the forms previously described. 25

All of the closures shown in Figs. 4 to 9 inclusive may be incorporated in the container and operate in the same way as the closure 14 in the form illustrated in Figs. 1, 2 and 3.

It will be noted, in the fully assembled condition of the parts as shown for instance in Figs. 1, 2, and 3, that the upper edge of the main section or body 10 constitutes an annular shoulder located within the receptacle formed by the main and secondary sections 10 and 11, on which annular shoulder the disk 12 rests, and that the closure 14 or its equivalent is rotatably held between said disk 12 and the internal bead 16 of the secondary section or sleeve 11. The combination of these parts in an operative structure is 35 effected in a simple manner by simply telescoping the sleeve 11 over the body 10 and fixing it in proper place thereon. The assembling of all of the parts of the container constitutes steps easily performed by competent operators and requiring 40 no particular skill in their performance. 45

In the arrangement shown in Fig. 10 the container comprises a body section 10^a, preferably of cylindrical form, and constituting a receptacle provided near its open end with an inwardly directed annular shoulder; the latter, in the form illustrated, comprises an inwardly directed annular supporting bead 10^b produced for instance by circumferentially indenting the body 10^a in any conventional manner. The annular supporting bead 10^b constitutes a rest for a disk 12^a which is dimensioned to snugly or frictionally fit the interior of the body section 10^a and corresponds to the disk 12 of the form first described. Like the latter, the disk 12^a is apertured in dependence upon the type of container with which it is to be combined and in accordance with the material for which the container is designed; in other words, the disk 12^a may be apertured to 55 sprinkle the contents of the container or to pour 60 the contents therefrom. For the purpose of exemplifying the aforesaid apertured arrangement, the disk 12^a is provided with a pouring aperture 13^a. 65

The latter or its equivalent is controlled by 70 means of a rotatable closure 14^a provided with a pouring opening 15^a arranged to be adjusted into and out of registry with the pouring aperture 13^a to selectively open and close the same at will; 75 it will be understood that, in this form also, the 75

closure 14^d is always apertured in a manner corresponding to the aperture arrangement of the disk 12^a and to enable the apertured portion of the latter and the apertured portion of the closure 14^d, to be brought into and out of registry with each other by rotatably adjusting the latter.

As in Figs. 1, 2 and 3, the closure 14^d is in the form of a disk dimensioned to easily and rotatably fit within the body section 10^a, and, in the operative position, rests upon and in surface engagement with the apertured disk 12^a. The closure 14^d may be maintained in its assembled relation in any convenient manner, and in the preferred construction projects beneath an internal holding bead 16^a formed preferably at the outer end of the body section 10^a. In practice the bead 16^a or its equivalent develops no material restraining effect upon the closure 14^d and does not interfere with the operative rotation thereof; at the same time said bead 16^a or its equivalent serves adequately to maintain said closure 14^d in place. Any convenient operating means may be provided to facilitate the rotation of said closure 14^d at will, which means may consist of 25 a hollow rib or projection 17^d as in Figs. 1, 2 and 3, or comprise any of the devices illustrated respectively in Figs. 4 to 9 inclusive.

The operation and functions of the container shown in Fig. 10 may otherwise be the same as in 30 Figs. 1, 2 and 3, and the advantages of the latter are also inherent therein.

The novel construction in all of its forms provides a dispensing container which is efficient in operation and capable of being produced at extremely low cost, thereby considerably increasing the field in which containers of the indicated type may be economically utilized. The novel arrangement is adaptable to containers over a wide range of dimensions and is capable of being incorporated 40 economically and efficiently in dispensing containers of specially small size and capacity.

Any materials conventionally utilized in the construction of customary containers, as well as materials which cannot be used to advantage in 45 existing types of containers, will be found acceptable in the production of the novel arrangement. Similarly, the novel features may be embodied in various combinations of materials, such as for instance metals and non-metallic substances, in the construction of the instant containers.

Various changes in the specific forms shown and described may be made within the scope of the claims without departing from the spirit of 55 the invention.

I claim:

1. A container comprising a cylindrical body having one end open, a cylindrical sleeve fitted over said body and fixed thereon against relative movement, said sleeve projecting axially beyond said open end of the body, an apertured disk fitted against relative movement interiorly of said sleeve and resting upon the open end of said body, an apertured closure in surface engagement with 60 said disk and rotatable thereon, an internal annular bead at the outer end of said sleeve whereby said closure is maintained in place without interference with its rotation, and means on said closure for rotating the same to adjust its apertured portion into and out of registry with the apertured portion of said disk.

2. A container comprising a cylindrical body having one end open, a cylindrical sleeve fitted over said body and fixed thereon against relative movement, said sleeve projecting axially beyond said open end of the body, a disk frictionally fitted against relative movement within said sleeve in engagement with the open end of said body, said disk being provided with an opening, an annular internal bead on said sleeve extending inwardly over said disk in spaced relation thereto, 10 and a rotatable closure in surface engagement with said disk and projecting beneath said bead, said closure having an aperture adjustable into and out of registry with the opening of said disk.

3. A container comprising a cylindrical body 15 having one end open, a cylindrical sleeve fitted over said body and fixed thereon against relative movement, said sleeve projecting axially beyond said open end of the body, a disk frictionally fitted against relative movement within said sleeve in 20 engagement with the open end of said body, said disk being provided with an opening, a rotatable closure in surface engagement with said disk and provided with an aperture adjustable into and out of registry with the opening of said disk, and 25 means whereby said closure is maintained in place on said disk without interference with its rotation relatively thereto.

4. A container comprising a main section and a secondary section, the main section fitting into 30 the secondary section and being fixed thereon against relative movement, said main section forming an annular shoulder in said secondary section, a disk frictionally fitted against relative movement within the secondary section in engagement with said annular shoulder, said disk being provided with an opening, and means movably mounted in said secondary section for controlling the opening in said disk.

5. A container comprising two sections telescopically fitted and secured together against relative movement, a disk frictionally fitted against relative movement within the one section in engagement with the end of the other section, said disk being provided with an opening, and 45 controlling means movably mounted in said one section in operative relation to said disk for controlling the opening in said disk.

6. A cover unit for containers consisting of a cylindrical sleeve, an internal bead at the one end 50 of said sleeve, an apertured disk frictionally fitted against relative movement within said sleeve in spaced relation to said bead, an apertured rotatable closure in surface engagement with said disk and projecting beneath said bead, and means for rotating said closure to adjust its apertured portion into and out of registry with the apertured portion of said disk.

7. A cover unit for containers consisting of a cylindrical sleeve, a disk frictionally fitted against 60 relative movement within said sleeve and provided with an opening, a closure in said sleeve in rotatable surface engagement with said disk and having an aperture means for maintaining said closure in operative relation to said disk without 65 interfering with the rotation of said closure, and means on said closure for rotating the same to adjust its aperture into and out of registry with the opening of said disk.
